UNITED STATES PATENT OFFICE.

JOSEPH K. PENFOLD, OF WARREN, OHIO, ASSIGNOR TO CLARENCE A. CRANE, OF WARREN, OHIO.

EXPANDING DEVICE.

No. 806,180.

Specification of Letters Patent.

Patented Dec. 5, 1905.

Application filed March 13, 1905. Serial No. 249,743.

To all whom it may concern:

Be it known that I, JOSEPH K. PENFOLD, a citizen of the United States, residing at Warren, in the county of Trumbull and State of Ohio, have invented certain new and useful Improvements in Expanding Devices; and I do declare that the following is a full, clear, and exact description of the invention, which will enable others skilled in the art to which it appertains to make and use the same.

My invention relates to an expanding device for sealing covers on vessels; and the invention consists in a device adapted to expand within limits on a true circle and enlarge a locking-ring in an expansible cover for white-lead kegs and other vessels, and thus lock the cover on the vessel, all substantially as shown and described, and particularly pointed out in the claims.

In the accompanying drawings, Figure 1 is a vertical sectional elevation of the expanding device with the segments thereof thrown down, as they are normally, and in which position they are contracted on their smallest circle. Fig. 2 is a vertical sectional elevation corresponding to Fig. 1 and with the segments spread and flattened out horizontally, as occurs when the cover and tightening-ring are expanded to locking position.

Fig. 3 is a bottom view of the expanding device partly sectioned away. Fig. 4 is a plan view of a cover for a can and the fastening-ring therein to be expanded. Fig. 5 is a perspective view of one of the several members of the group of expanding-segments adapted to engage the ring except at its overlapping ends. Fig. 6 is a view of a modification of ring, showing an uncut ring.

The invention as thus shown is designed to be employed especially in the fastening of covers or caps on metallic kegs for white lead, paints, varnish, and the like. These kegs or cans are comparatively small generally, those used for white lead especially not having a capacity exceeding a gallon or somewhat less in measurement. However, exactness of size is not material, and neither are the contents, whether they be lead, paint, or other material; but it is material to this invention that the vessel or keg A be metallic, and it is preferably made out of suitable sheet or plate metal shaped to the size and contour, say, of a keg and constructed about

its top with an inturned flange *a* or its equivalent to provide a seat upon which the cap or cover C may be hermetically sealed. The said cap or cover C is preferably fashioned as shown and in this form has a wall *c* about its outside substantially at right angles to the flat body portion *c'* of the cover and has its edge extended into a roll *c*², adapted to seat over the flange *a* of the keg. Any suitable seat serving the purpose of seat *a* may be employed, and this is true also of the engaging edge of the cap; but it is essential to both that when they are pressed together they will hermetically seal the keg and firmly lock the cover thereon. Any construction that will secure these essential objects will suffice and be within the scope of my invention, provided, however and further, that such construction is capable of being fastened by means of an expanding-ring D. In this instance and preferably I employ a split or cut ring having overlapping ends and fitting within and about the base of the cover in this condition. The measure of expansion of both the ring and the cover is fixed by said ring, and the idea is to spread the ring until the ends will spring into abutment one against the other and which is their maximum expansion. I might, however, use a whole or uncut ring of ductile metal and expand it to the dimensions required herein, and it would serve all the purposes of the split ring, and such a ring is shown in Fig. 6 and marked D'.

Now having the several parts provided as above described and the keg filled, presumably, with white lead, the next step is to secure the cover thereon, and this brings this description directly to the means for accomplishing this purpose.

Having both a cover and a fastening-ring to expand and secure the cover, I have devised an expanding mechanism comprising a suitable head H, having a shank *h*, adapted to be engaged in any suitable down press and carrying about its bottom a series of segments G. These segments in the aggregate constitute a complete circle extending some distance out beyond the edge of head H and provided with a rounded bearing *g*, socketed in a corresponding channel *h'* in the bottom of said head and in which they are confined by disk J, overlapping said bearings or shanks

g at the bottom and confining the segments, while they have perfect freedom of play up and down within limits. The upward limit is their engagement against the bottom of head *H*, Fig. 2, and their downward limit or drop is against disk *J* at their shoulders *g'*, Fig. 1. The disk *J* is rounded about its top edge to conform to the groove *h'* in head *H* and complete the seat for the segments.

10 A ring *L* rests about the base of head *H* upon the several segments equally, and a series of springs *l*, socketed therein and in head *H* and placed at intervals, serve to exert a normal downward pressure upon said ring, and thus keep the segments in their narrowest and depressed position, as in Fig. 1. Then as power is applied for expansion the said segments have a maximum expansion, as in Fig. 2, in which position they not only spread ring *D*, but cause its ends to come together in abutting and locking relation. In this operation the wall *c* of the cover is in like measure spread and enlarged about its base, so that it forms a distinct bead externally, which engages beneath the edge of the inturned or seating surface or portion *a* of the keg.

15 20 25 30 35 40 45 50 55 60 65 70 75 80 85 90 95 100 105 110 115 120 125 130

All the segments *G* are provided with transverse grooves or shouldered offsets *g²* in their outer wider ends and in the lower edges thereof where they bear against ring *D*, so as to hold the said ring down where they engage the same in the expanding operation; but the segment *G'*, which comes at the front opposite the inner end *d* of the ring, necessarily has a recess or offset *g³* of greater depth than the recess *g²* in the other segments, and so it follows when the ring is fully expanded the end *d* thereof will spring or snap into line with and engage the end *d'*, and thus become locked and lock the cover on the keg. When down pressure on the device is relaxed, the several segments are thrown down into normal position again and the device is ready for another operation. Slight projections *g⁴* are shown on the shanks or bearings of the segments, which keep them apart, and such projections may be located in any other position where they will do the work and keep the segments uniformly spread and separated. Segment *G'* really is an idle member except as it fills a space in the circle of segments; but it does not bear against the ring, as the others do. If the ends *d* and *d'* of the ring should fail to exactly lock in a single depression, the device can be rotated slightly and depressed again, which will cause them to lock effectually.

A pin *n*, engaging in a slot *n'* in one of the series of segments *G*, serves to keep them all from rotating together in their bearings, and the said segments may be relatively larger or smaller than shown and serve my purpose. However, for all purposes the present proportion is a preferred size. Usually the said

segments or members are cast; but they may be radially sawed out of a single piece of metal suitably fashioned for this purpose.

In operation cover *C* is first placed on the keg. Then the ring *D* is placed therein about the base of the cover and against the vertical wall thereof, or cover and ring may come to the keg assembled, and last of all the spreading or expanding device is lowered and depressed by power. In this operation some of the pressure comes upon the keg or vessel; but the great pressure is lateral against the ring *D* and the cover, and the metal of the cover is thin enough to effect a distinct rib in the wall thereof opposite the ring on the outside to make locking engagement with seat *a* of the keg.

The lips or overhanging portions at the top and outer edge of the segments bear upon the ring and hold it down while the expansion thereof is in progress, and all the segments are designed to exert a like pressure uniformly except segment *G'*, which in a sense is an idler.

What I claim is—

1. In devices for securing covers on cans and other vessels, a series of radially-disposed members having their outer edges curved to the segment of a circle, a head from which said segments are pivotally suspended at their inner ends at a downward inclination and a device adapted to exert a yielding pressure downward on said members between their ends, whereby when said members are pressed to a horizontal position they spread on a larger radius and separate laterally.

2. A device for securing covers on vessels comprising a head constructed to apply power on the top thereof, a series of segments having outer curved edges disposed in a circle about the bottom of the said head, means fixed to the bottom of the said head overlapping the inner bearing ends of said segments, and means about the outer portion of said head to exert a yielding downward pressure on said segments.

3. A device consisting of a circular head provided with a shank to make power connection, a series of laterally-spreadable segments pivotally supported on the under side of said head, and a support centrally beneath said head overlapping the inner bearing ends of said segments and constructed with an annular shoulder engaging the portions of said segments at their inner ends to afford uniform support therefor.

4. The head having a shank on its top and a groove about its edge and bottom, in combination with a series of radially-disposed segments having rounded bearings resting in said groove, a confining-disk engaging said bearings beneath said spring-pressed mechanism bearing upon the top of said segments.

5. A device for securing covers on metallic

vessels in which there is an expansible ring, the same comprising a suitable head and a series of segments radially and pivotally disposed about the same, stops to limit the movements of said segments on their pivots and the said segments constructed at their outer edges with grooves to engage said ring.

In testimony whereof I sign this specification in the presence of two witnesses.

JOSEPH K. PENFOLD.
